UNITED STATES PATENT OFFICE.

RUSSELL C. STOKES, OF PORTLAND, OREGON.

SAND-MIXING MACHINE.

1,337,373.

Specification of Letters Patent. Patented Apr. 20, 1920.

Application filed September 22, 1919. Serial No. 325,415.

To all whom it may concern:

- Be it known that I, RUSSELL C. STOKES, a citizen of the United States, residing at Portland, in the county of Multnomah and 5 State of Oregon, have invented a new and useful Improvement in Sand-Mixing Machines, of which the following is a specification, reference being had to the accompanying drawings.
- 10 My invention relates to a class of devices for mixing sand which has been employed in foundry molding.

The object of my invention is to provide a device, by the employment of which the 15 sand is kneaded toward the center of the path of travel of the machine, and at the same time is thoroughly separated into its loose granular condition. I attain these objects, as well as other advantages, by the 20 construction, combination and arrangement of parts illustrated in the accompanying drawings which form a part hereof.

Figure 1 is a side elevation of the device.

Fig. II is a plan view with parts removed. 25 Fig. III is a rear elevation of mixer drum. Fig. IV is an end elevation of the same.

Fig. V is a sectional elevation of clutch releasing mechanism related to the drum.

Fig. VI is a sectional view on the line 30 VI—VI in Fig. V.

Like numerals refer to like parts in the views.

A carriage 7 is provided with a single forward pivoted steering wheel 8, having a 35 steering handle 9, and two rear wheels 10—10'. In the rear part of the carriage, angled wheel axles 11—11' are rigidly secured in desired positions and upon the lower ends of these the wheels 10—10' are 40 rotatably mounted. An electric motor 12 is arranged upon a frame 13, secured over the carriage. The motor has a drive shaft 14, from which a chain belt 15 extends to a toothed wheel 16 on a transmission shaft 18, 45 which is rotatably mounted longitudinally of the carriage in bearings 19—19'. The shaft 18 is horizontally slideable in its bearings and has a transverse friction disk 20 rigidly secured on its rear end. A collar 21 50 is adjustably secured to the shaft 18 adjacent to the bearing 19 against which it rotates. Adjacent to the bearing 19' another collar 22 is secured upon the shaft 18 and rotates with the same. The collar 22 has a groove 23. A lever mechanism 24 has a fulcrum at 55 25, secured in the carriage, and a pin 26 ar-

ranged to engage the collar 22 in its groove 23. An eccentric operating handle 27 is arranged upon the carriage frame to move this lever mechanism. Between the collars 60 a coil spring 27 is placed about the shaft 18, the ends of the spring engaging the collars and in this manner forcing the shaft and its disk rearwardly. To the rear of the disk 20 a friction pulley 28 is rigidly secured on 65 a transverse rotatable shaft 29 and in position to be engaged by the disk 20. The pulley 28 is keyed upon the shaft in a manner to allow it to be slid along the shaft, in order to engage the disk in varying positions. 70 The pulley has a rigid grooved hub 30. A lever 31 is pivotally mounted in a position to engage the pulley 28 in its grooved hub, in a manner whereby the pulley may be moved along the shaft by the lever. The 75 shaft 29 has a worm 32 near its outer end. Transversely below the shaft 29 is a shaft 33 provided with a rigid beveled gear 34 on one end and a worm gear 32' below the worm 32 and in position to engage it. On the opposite end of the shaft 33 is a rigid pulley 80 35. Rearwardly from and parallel with the shaft 29 is another rotatably mounted shaft 40. Upon the inner end of said shaft is a rigid beveled gear 41 in position to be engaged by the gear 34. A toothed wheel 42 is mounted in clutch mechanism on the outer part of this shaft in a manner whereby the wheel may be thrown into engagement with the shaft to cause it to rotate and be released 90 from rotating engagement on the shaft. The clutch mechanism is operated by the lever means 43. A toothed wheel 44 is rigidly secured to the tractor wheel 10 and a chain belt 45 extends about the wheels 42 95 and 44.

Angled drum supports 46—46' are pivotally mounted at their forward ends on the wheel axle supports, where shaft formed adjacent to the carriage frame. The supports 46—46' have a drum shaft 47 pivoted in their angles, upon which a drum 48 is rigidly mounted. On the lower ends of the drum supports 46—46' small drum carrying wheels 49 are rotatably mounted in adjustable means 49'. The drum is provided with rigid helical blades 50 on each end. The drum has a series of transverse bars 51 secured to drum spiders 48a and to these bars 51 are hinged the bars 52 which are provided with fingers 53. The central parts of the bars 52 have arms 54 and springs 55 con-

necting the same to opposing bars 51. Upon one end of the drum shaft a power gear wheel 56 is rotatably mounted. Upon the shaft 47, and adjacent to the wheel 56, 5 clutch mechanism 57 is arranged, with a spring 58 to retain the clutch in engagement and lever means 59 to release it from engagement with the wheel 56. A pin 60 extends into a socket of the lever means and its opposing end is in a position wherein the bars 52 may engage the pin 60 when the bars are pressed by obstacles beyond the desired distance, and force the pin into the socket and actuate the lever means to release the 10 clutch. A spring 61 retains the pin out of engagement with the clutch lever means at other times. This clutch and lever means are shown in Figs. V and VI.

In alignment with the shaft 29 another shaft 62 is rotatably mounted and has upon it a friction pulley 63 in a position to be engaged by the disk 20, the pulley being keyed upon the shaft in a manner to allow it to be slid along the same, in order to engage the disk in varying positions. The pulley 63 has a rigid grooved hub 64. A lever 65 is pivotally mounted in a position to engage the grooved hub in a manner whereby the pulley may be moved along the shaft by the lever. Near the opposite end of the shaft a gear 66 is rigidly secured. Rearwardly from the shaft 62 another transverse shaft 67 is rotatably mounted. Upon this shaft is a gear 68 and a drive chain 69 extends about the gears 66 and 68. On the opposite end of the shaft 67 a gear 70 is rigidly secured. Adjacent to the support 46 and upon the upper shaft formed 30 end of the axle 11 is a rotatable sleeve 71, 35 to which a gear 72 is rigidly secured. A drive chain 73 extends about the gears 70 and 72. Adjacent to the gear 72 another gear 72' is rigidly secured upon the sleeve 71. A drive chain 74 extends about the 40 gears 56 and 73.

Above the motor a reel 75 is rotatably mounted on a shaft 76 provided with a pulley 77. A belt 77' extends about the pulleys 35 and 77. An electric cable 78 extends 50 from a power source to the motor and is wound upon the reel as the machine advances in the direction of the power source. A guard 79 extends rearwardly over the drum. Lines 80 are connected at their lower 55 ends to the drum supports 46 and extend upwardly to and through hoisting mechanism 81 which is operated by the rod 82 through the related worm and gear when it is desired to adjust the height of the drum 60 above the path of travel of the machine.

It will now be seen that when electric power is transmitted to the motor 12 this power is transmitted through the intervening mechanism to the tractor wheel 10, the 65 arrangement of the gears providing for a

moderate speed of the machine over its path of travel. Also, the traction power being applied to one wheel only, obviates the need of differential gearing required for a two tractor drive. The machine being arranged 70 with one forward steering wheel and one tractor wheel drive, allows it to be turned in a less radius or pivotal center than a four wheel carriage. It will be further seen that power is transmitted from the 75 motor through intervening mechanism to the drum and this mechanism is arranged to provide a high speed in the drum revolutions. The helical drum blades knead the sand inwardly toward the center as the machine straddles a pile of sand, from which foundry castings have been removed. The fingers of the drum enter the sand thus kneaded and thoroughly develop it into 80 loose granular condition adapted for renewed use in molding or casting. The sand is thus broken up and mixed far better than is done by machines equipped with cutting blades only. The fingers in my device also cast the sand rearwardly in the path of 85 travel in this same granular condition, which result has not heretofore been attained. The mechanisms for shifting the friction pulleys 28 and 63 on the friction disk 20 allow a wide range of speeds for the 90 traction and the drum, which is highly useful, whereas in other known devices not more than two rigidly pre-determined speeds are attainable. The series of mixing fingers are hinged and given resiliency by the bar 100 holding springs which prevents the fingers from breaking when meeting unusual resistance. The automatic mechanism which releases the drum from operative movement is provided for cases where the fingers strike 105 an obstacle which they can not pass or throw aside. This prevents injury to the fingers and other mechanism. The helical blades also insure a rigid piling of the sand. They require less power to cause 110 their helical movement through the sand than blades arranged only to stir or agitate it with the consequent resistance thereby to be overcome.

It will be apparent also that the hoisting 115 means for the drum permits the drum to be adjusted at a convenient height above the path of travel and secured there, either while the machine is mixing sand or being moved away from it. Mechanism is also 120 provided to stop the tractor wheel at any time, while the drum continues to be rotated. The reel mechanism is arranged in connection with the traction transmission in order that the power cable may be picked 125 up with relation to the speed of travel of the machine. It will also be seen that means are provided to release the friction disk and stop the transmission of power to both tractor wheel and drum. The guard is pro- 130

vided to prevent sand being thrown forwardly upon the mechanisms. The mechanism for changing the positions of the friction pulleys on the friction disk, amply provides an efficient means to gradually increase or decrease the speed of the drum or the tractor, and obviates jolting, sudden movement or stoppage, which feature is of great importance in sand mixers.

10 The drum supporting wheels are adjustable, by the means shown, in a manner to retain the drum at a desired height over the travel path. The drum also being pivotally mounted on its supports, this allows it to be carried over uneven floor surfaces and to automatically adjust itself to them during its progress through the sand. These are also important features in my device.

I claim:

20 1. In a machine of the character described, the combination therein of, a chassis, a drum rotatably mounted therein, sharply pitched helical blades upon and about the outer parts of the drum for a desired distance toward its center, and arranged in a manner to allow them to engage and cast material below them toward the center of the path of travel of the chassis, a plural series of fingers extending outwardly

25 from the drum between said blades, means to retain said fingers in resilient position, mechanism in the chassis arranged to transmit power from a source therein to allow one rear wheel thereof to be rotated at a desired speed, and mechanism in the chassis arranged to transmit power independently from the same source to allow said drum to be rotated at a desired speed differing from that of the chassis, for the purposes indicated.

30 2. In a machine of the character described, the combination therein of, a chassis, a drum rotatably mounted therein, sharply pitched helical blades upon and about the outer parts of the drum for a desired distance toward its center, and arranged in a manner to allow them to engage and cast material below them toward the center of the path of travel of the chassis, a plural series of fingers extending outwardly from the drum between said blades, means to retain said fingers in resilient position, and mechanism in the chassis whereby power may be transmitted from a source

35 in the chassis to allow said drum to be ro-

tated at a desired speed, for the purposes indicated.

3. In a machine of the character described, the combination therein of, a chassis, a drum rotatably mounted therein, sharply pitched helical blades upon and about the outer parts of the drum for a desired distance toward its center, and arranged in a manner to allow them to engage and cast material below them toward the center of the path of travel of the chassis, for the purposes indicated.

4. In a machine of the character described, the combination therein of, a chassis, a drum rotatably mounted therein, sharply pitched helical blades upon and about the outer parts of the drum for a desired distance toward its center, and arranged in a manner to allow them to engage and cast material below them toward the center of the path of travel of the chassis, a plural series of fingers extending outwardly from the drum between said blades, means to retain said fingers in resilient position, mechanism in the chassis whereby power may be transmitted from a source in the chassis to allow said drum to be rotated at a desired speed, and clutch mechanism arranged to automatically allow the drum to be released from its engagement with said power transmitting mechanism when said fingers are pressed toward the drum a pre-determined distance, for the purposes indicated.

5. In a machine of the character described, the combination therein of, a chassis, having two rear and one forward pivoted steering wheel, and mechanism in the chassis arranged to transmit power from a source therein to allow one rear wheel to be rotated at a desired speed, for the purposes indicated.

6. In a device of the character described, the combination therein of, a chassis, a frame pivoted in the chassis, a drum rotatably mounted in the frame, supporting wheels rotatably mounted in the frame, and mechanism in the frame to allow the wheels to be positioned in a manner whereby the drum may be carried at a desired height above the chassis travel path, for the purposes indicated.
